METHOD OF SCARFING METAL SLABS

James L. Anderson, Closter, N. J., assignor to Air Reduction Company, Incorporated, a corporation of New York

Application April 1, 1947, Serial No. 738,757

2 Claims. (Cl. 148—9.5)

1

This invention relates to an improved method of scarfing metal slabs. By "scarfing" is meant projecting a row of oxygen jets at an angle against the work surface to be scarfed while the metal is at kindling temperature, and moving the work past the jets to progressively remove the surface metal by thermo-chemical action.

Heretofore, in scarfing relatively wide slabs it has been the custom to pass the slab through the scarfing machine in a horizontal position and scarf the bottom face only in one pass through the machine, then return the slab, turn it over, and pass it through the machine a second time to scarf the opposite face. The reason why it has not been practicable to scarf the top face of the slab is that molten slag forms in a puddle in front of the oxygen jets and becomes of considerable size due to the relatively great width of the slab. The puddle is pushed along in front of the oxygen jets and eventually runs off the sides and end of the slab and down over the mill rolls on which the slab is supported. The slag sticks to the rolls and creates an undesirable condition. This is not avoided when scarfing wide slabs in mills where the distance between successive rolls is short even if the oxygen jets are obliquely directed toward one edge of the slab to blow the molten slag toward and over such edge, because all of the slag can not be blown laterally off the slab in this manner within the distance between successive rolls. There is no similar problem in scarfing the bottom face of a slab because the slag drops off the work by gravity directly into the pit and the flying slag blown off of the slab surfaces by the oxygen jets can be stopped by a baffle in front of the mill roll ahead of the scarfing area and it will fall harmlessly into the slag pit.

The principal object of this invention is to make it possible to scarf both wide faces of a slab simultaneously, or all four faces if desired, without the slag getting on the mill rolls.

This object is attained by manipulating a slab that is being fed to the scarfing station in a horizontal position to turn it on edge to a vertical position, and scarfing the wide faces of the slab while they are in vertical position, and also the top and bottom edge faces if desired. Thus the molten slag from the wide faces is carried off rapidly by gravity, which may be assisted by having the scarfing jets directed downward as well as at an angle toward the slab faces. After the slab has passed the scarfing means it is returned to horizontal position and allowed to pass on to the next mill operation.

2

Apparatus suitable for use in carrying out the method is illustrated in the accompanying drawings, in which:

Figure 1 is a plan view of a portion of a slab mill with scarfing apparatus embodying this invention;

Fig. 2 is a vertical transverse section taken on the line 2—2 of Fig. 1;

Fig. 3 is a plan view of the scarfing apparatus shown in Fig. 2;

Fig. 4 is a perspective view showing part of the scarfing means and a slab being scarfed thereby;

Fig. 5 is a vertical transverse section taken on the line 5—5 of Fig. 1;

Fig. 6 is a vertical transverse section taken on the line 6—6 of Fig. 1;

Fig. 7 is a vertical transverse section taken on the line 7—7 of Fig. 1; and

Fig. 8 is a vertical transverse section taken on the line 8—8 of Fig. 1.

As shown in the drawings, a series of horizontal feed rolls 11 support and drive a slab (not shown) between the heads 12 and 13 of a manipulator. These heads are movable horizontally in a direction parallel to the axes of the rolls 11. The head 13 is secured to two bars 14 whose undersides have rack teeth engaging pinions secured to a shaft 15. The shaft 15 is driven by a motor 16 through a coupling 17 and a set of reduction gears enclosed in a housing 18. Thus rotation of the motor 16 causes rotation of the shaft 15, moving the manipulator head 13 horizontally above the rolls 11.

The head 12 is moved in a manner similar to the head 13. A motor 19 drives reduction gears enclosed in a housing 20, rotating a shaft 21. The shaft 21 has pinions attached which engage the rack teeth on the bars 22 to which the head 12 is rigidly secured. Thus rotation of the motor 19 produces horizontal motion of the head 12 in a direction perpendicular to the direction of travel of the slab.

Pivotedly mounted in bearings 23 on the head 12 is a shaft 24 to which bell cranks 25 are rigidly attached. These cranks pivotally support hook members 26 which lie in recesses in the manipulator head 12. The hooked portions of the members 26 fit between rolls and can be lowered below the plane of the mill table (Fig. 5). Two motors 27 and 27' (Fig. 1) are connected by spur gears 28 to a shaft 29 and a gear train 30 to rotate the cranks 31 in one direction or the other. These cranks 31 are connected to the upper ends of the bell cranks 25 by links 32 and movement of the cranks 31 is transmitted through the links

32 and bell cranks 25 to the hook members 26. By combining the motions of the manipulator heads and the hook members 26, a slab can be turned on edge or turned over as desired. Such manipulators are well known in the art.

The scarifying heads are carried by carriages best shown in Figs. 2 and 3. A carriage 33 is propelled along a track 35 by a motor 37 which is remotely controlled by the operator. The carriage has an axle 38 connected to driving wheels 39, and there is a worm wheel 40 secured on the axle 38. The worm wheel is engaged by a worm 41 rotated by the motor 37 through a bevel gear train 42. A bracket 43 (Fig. 8) holds a block 44 close to one side of the carriage to prevent the moving slab from tipping the carriage when the carriage is in operative position. Another carriage 34 on the other side of the mill table is propelled along a track 36 by mechanism similar to that of the carriage 33.

Mounted on the base of the carriage 33 is an air motor 45 (Figs. 2 and 3) which movably supports a frame 46. A counterweight 47, acting through a system of pulleys 48, partially relieves the load on the air motor 45. The frame 46 is guided in its vertical movement by pins 49 extending from the frame 46 and running in slots 50 in the carriage walls. The frame 46 carries an air motor 51 which is connected to the scarifying head 52. A stop 53 limits the upward travel of the frame 46 to prevent the lower scarifying tip from rising above the roll table level. Two guide rods 54 are also connected to the scarifying head 52 and support it from the frame 46. These guide rods 54 slide in the frame 46 to permit movement of the scarifying head 52 transversely of the mill table when the motor 51 is actuated.

The scarifying head 52 which is supported from the carriage 33 comprises a support bar 55 and the attached tips 56 for scarifying both a vertical face and the bottom edge face of a slab when the slab is in the vertical position shown. Gas lines are shown for supplying oxygen and acetylene to the scarifying heads. The torch tips may be of the block type and preferably have their oxygen streams directed not only at an angle to the slab faces being scarfed but also at an angle to the direction of motion of the slab as shown in Fig. 4.

It is evident that with the above described apparatus the carriage 33 can be moved in or out of the scarifying area by means of the motor 37 and the scarifying head can be positioned vertically or horizontally by manipulation of the motors 45 and 51. This universal movement allows the scarifying head 52 to be positioned against the slab being scarfed and to follow irregularities in the size and shape of the work-piece.

The carriage 34 similarly supports a scarifying head 59 which serves to remove the surface metal from the other vertical face and the top edge face of the slab.

The downward inclination of the jets acting on the wide vertical faces of the slab assists gravity in rapidly deflecting the slag down between successive rolls of the mill table, and the lateral inclination of the jets acting on the narrow top edge face of the slab blows the slag off this face within the longitudinal distance between mill rolls.

The carriages and hence the scarifying heads are offset one from the other, as shown in Fig. 3, to allow the heads to close sufficiently around a slab to accommodate considerable tolerance in the

dimensions of the slab. The trailing head 52 scarfs that wide vertical face toward which the slag from the top edge face is directed (Fig. 4).

A series of horizontal feed rolls 60 (Fig. 1), similar to rolls 11, support and drive the work-piece beyond the scarifying area. These rolls, as well as the feed rolls 11, may be power driven in accordance with conventional practice. A series of fixed vertical rolls 61 and movable vertical rolls 10 62 are provided to guide the slab as it emerges from the scarifying area. The water curtains for slag quenching are not shown since their illustration is not necessary for a complete understanding of this invention.

15 The fixed vertical rolls 61 (Fig. 6) are supported by stationary webbed brackets 63. The movable vertical rolls 62 are supported by webbed brackets 64 which slide on tracks 65 (Fig. 8). Air motors 66 advance and retract the movable vertical roll assemblies and are remotely controlled by the operator. The movable rolls 62 may be retracted far enough to permit a slab to pass through the apparatus while lying horizontally.

20 Alternately spaced between the vertical guide 25 roll assemblies are handling units to lay the slab down from its vertical position to a horizontal position on the mill table. These handling units comprise two pivotally mounted arms 67 and 68 (Fig. 7) and their respective supports and 30 drive mechanisms. The arms 67 are pivotally mounted at 69 on brackets rigidly attached to the mill table frame. Short stroke air motors 70 are mounted on brackets 71 behind the arms 67 and linked to the arms 67 so that actuation of the 35 motors 70 causes limited angular rotation of the arms 67 about the fixed pivots 69.

The arms 68 pivot about the shaft 72 and each of the arms 68 has a crank 73 extending below the shaft 72 and connected by a link 74 to a crank 75 secured to a shaft 76. The shaft 76 is driven by a motor 77 through reduction gears 78, coupling 79, and a worm 80 which engages a worm wheel 81 secured to the shaft 76.

45 The operation of the apparatus shown is as follows: A slab is conveyed along the mill table from left to right (Fig. 1) and is positioned on the rolls 11 between the manipulator heads 12 and 13 with its wide faces horizontal. To allow the slab to be positioned between the manipulator heads in this position, the heads must be withdrawn to the edge of the mill table. By means of the remotely controlled motors 16 and 19 the manipulator heads are brought toward each other properly aligning the slab on the mill table for subsequent operations. The motor 27 is then energized causing rotation of the shaft 24 and upward movement of the hook members 26. This raises the edge of the slab, positioning the slab at a great enough angle to allow further advancement of the head 13, which pushes the slab before it, and causes the edge of the slab held up by the hook members 26 to slide up the face of the head 12. During this latter part of the manipulation of the slab, the motor 27 is operated to return the hook members 26 to their original positions. The head 13 is advanced until it closes on the slab and puts the slab in a vertical position. The slab is then positioned, if necessary, in line with the scarifying apparatus.

70 Rolls 11 then advance the slab in its vertical position to the scarifying station. The scarifying heads are brought into the scarifying area by advancing the carriages 33 and 34. The air motors 45, 45', 51 and 51' (Fig. 2) are then actuated to 75 position the scarifying heads against the slab. The

preheat flames are turned on to bring a portion of the slab to kindling temperature and then the scarfing oxygen is started and the slab is advanced.

As the leading edge of the slab emerges from the scarfing area it is guided by the vertical rolls 61 and 62 positioned as shown in Fig. 1. When the trailing edge of the slab leaves the scarfing area, the gases are shut off and the slab brought to rest between the vertical rolls.

Arms 67 and 68 (Fig. 7) are vertically disposed and upon the withdrawal of the movable vertical rolls 62, the arms 68 maintain the slab in its vertical position. To lay the slab down and prepare to pass it to the next mill operation the motor 71 is operated to tilt the arms 68 and the air motors 70 are then actuated to tip the slab over against the arms 68. The motor 71 then is operated to rock the arms 68 about the shaft 72 and lower the slab to a horizontal position. Shaft 72 is below the plane of the mill table and the arms 68 travel down between the mill rolls to bring them free and clear of the slab on the table.

Should the election be made to pass a slab through the mill unscarfed, the carriages 33 and 34 are fully withdrawn as are the movable vertical rolls 62, and the arms 68 are put in their horizontal position clearing the mill for passage of a slab horizontally.

It will now be seen that the invention makes it possible to scarf both wide faces of a slab simultaneously without slag getting on any of the mill rolls. In fact, all four faces of the slab may be scarfed simultaneously if desired without encountering this difficulty. This reduces the operation to one pass of the slab through the scarfing machine instead of two as heretofore which, of course, results in a considerable saving of time. While the invention makes it possible to scarf both wide faces of the slab simultaneously, only one of them may be scarfed while the slab is in vertical position should this be desired for any reason. When no scarfing at all is required the slab may be passed through the entire apparatus in horizontal position.

I claim:

1. The method of scarfing metal workpieces

having a rectangular cross-section and having two relatively wide opposite faces each of which is too wide to be successfully scarfed in a single pass as a top horizontal surface and having two relatively narrow opposite faces each of which is narrow enough to be successfully scarfed in a single pass as a top horizontal surface, which comprises positioning the workpiece with said relatively wide surfaces disposed substantially vertically, advancing the workpiece while so positioned past the scarfing station and there directing scarfing jets of oxygen simultaneously against both of the relatively wide vertically disposed faces and against both of the relatively narrow horizontally disposed faces.

2. The method of scarfing metal workpieces having a rectangular cross-section and having two relatively wide opposite faces each of which is too wide to be successfully scarfed in a single pass as a top horizontal surface which comprises positioning the workpiece with said relatively wide surfaces disposed substantially vertically, advancing the workpiece while so positioned past the scarfing station and there directing scarfing jets of oxygen simultaneously against both of the relatively wide vertically disposed faces.

JAMES L. ANDERSON.
